UNITED STATES PATENT OFFICE.

MAURICE R. BROWN, OF AMSTERDAM, NEW YORK.

MATHEMATICAL MODEL.

Application filed July 30, 1924. Serial No. 729,195.

To all whom it may concern:

Be it known that I, MAURICE R. BROWN, a citizen of the United States, residing at Amsterdam, in the county of Montgomery and State of New York, have invented a new and useful Mathematical Model, of which the following is a specification.

My invention relates to mathematical models, and more particularly to models by which the truth of certain geometric theorems may be readily demonstrated for any and all cases.

Geometry, as ordinarily taught, involves the study of static figures illustrating or demonstrating one particular case of a theorem, and it is impossible to illustrate by ordinary methods the infinite resultant variations in functional values occurring from relative changes in the magnitudes of which the resulting values are functions. The pythagorean theorem, and the theorem that any right triangle may be inscribed in a semi-circle, for example, are fundamentals of plane geometry which should be thoroughly understood by the student, and all cases of which are susceptible of practical demonstration by a working model.

The object of my invention, therefore, is to provide a mathematical model of cheap and simple construction, which may be easily operated, which will illustrate in a dynamic manner the resulting variations in the mathematical squares of the two legs of a right triangle as they may vary in relative length, and which will incidentally demonstrate that the locus of the vertex of a right triangle having a hypotenuse of fixed length as a base, is a semi-circle.

With this object in view, my invention consists in the novel combinations, arrangements, and cooperative relations of the parts forming my model, one form of which is illustrated in the accompanying drawing, in which—

Fig. 1 is a front elevation of my device; Fig. 2 is a front elevation showing the elements of my model in a slightly different relative position; and Fig. 3 is a plan view looking down on Fig. 2.

Referring to the drawing, 1 is the base of my device which may be of wood or any suitable material upon which the mechanism may be mounted. For the purpose of explaining my device, it will be assumed that the square, 2, having four sides, each two

units, N, in length, is erected upon the base, although the actual erection while desirable is not essential. At the mid point of the opposite sides, 3 and 4, similar cranks, 5 and 6, which may be of stiff wire, are axially mounted in the base and have small loops or eyes, 7, formed in their extremities, and have operating arms, 8 and 9, respectively, behind the base, which are preferably bent at right angles to the crank or arms, 5 and 6, substantially as shown. The length of the cranks, 5 and 6, between the axis of rotation and the eyes, 7, is one unit, N. In the center of the square, 2, a crank having rectangularly disposed arms, 10 and 11, is axially mounted in the base, and has an operating arm, 12, behind the base, equal in length to the arms, 8 and 9, and disposed so as to bisect the angle between the arms, 10 and 11. The arms, 10 and 11, are equal to each other and $N\sqrt{2}$ units in length between the center of rotation and loops, 7, which are formed at the extremities.

It will be evident that the loci of the center of loops 7, on cranks, 5 and 6, are circles, 13 and 14, respectively, of radius, N; and the locus of the center of loops, 7, on cranks, 10 and 11, is a circle, 15, having a radius, $N\sqrt{2}$.

At the lower corners of square, 2, screw eyes or the like, 16 and 17, are inserted in the base with their axes at right angles, as shown. A flexible filament, 18, such as string or thread, is then threaded through the eyes, 7, 16 and 17, in the direction of the arrows shown thereon, and a weight, 19, is suspended in the loop, 20, below the screw eye, 17, as shown.

In adjusting the mechanism, the cranks, 10 and 11, may be turned until loops, 7, at the extremities thereof, coincide with corners, 21 and 22, respectively, of square, 2; and cranks, 5 and 6, should be turned until they are horizontal, with the loops, 7, at points, 23 and 24, respectively. When the cranks are in this relative position, the arms, 8, 9 and 12, should be substantially parallel and may be connected by the operating bar, 25.

It will be apparent from a consideration of the drawing, Figs. 1 and 2, that the filament, 18, appears to cross itself at right angles at point, 26, which forms the vertex of a right triangle having the base, 27, of

square, 2, as a fixed hypotenuse; and that the locus of point, 26, as the cranks are moved by the operating bar, 25, is a semi-circle, 28. It will also be apparent that the filament, 18, forms two squares, each representing the mathematical square of a leg of the right triangle. As the cranks are moved equal angular amounts by the operating bar, the vortex, 26, will assume different positions in its locus, 28, and the squares formed by the filament will vary in size and area as the legs, 29 and 30, of the right triangle, vary in length. The filament, 18, will slide through the loops, 7, and eyes, 16 and 17, and it will be kept always taut by weight, 19, so that the outlines of the triangle and squares will be perfectly straight. Thus it will be evident that my model may be used to demonstrate every possible case of the pythagorean theorem; and, if the semi-circle, 28, be described on the base, every possible right triangle will appear to be inscribed therein as the vertex, 26, is made to move about its locus.

It is obvious that many changes may be made in my device such as substituting a spring for weight, 19, or by dispensing with either a weight or spring by using an elastic filament such as rubber. It is also obvious that the rectangularly disposed cranks, 10 and 11, are not essential features of my device, it being merely essential that the relative position of the loops at the extremities thereof be maintained as described by any suitable means. These, and other changes of a similar character may clearly be made without departing from the scope and spirit of the appended claims.

What I claim is—

1. A mathematical model comprising flexible means forming the legs of a right triangle and two squares; a side of each square forming a leg of said triangle; and means for varying the sizes of the squares.
2. A mathematical model comprising a flexible filament outlining the legs of a right triangle and squares having sides coincident with said legs, and rotatable means cooperating with the filament at corners of said squares for varying the sizes thereof.
3. A mathematical model comprising flexible means outlining a square having a side thereof forming the leg of a right triangle, and means for varying the length of said leg and maintaining the area of said square proportional to the mathematical square of the length of said leg.
4. A mathematical model comprising a filament of flexible material forming the legs of a right triangle and squares proportional in area to the squares of said legs, and means cooperating with said filament at the corners of said squares for simultaneously varying the legs of said triangle and maintaining the areas of said squares pro-

portional to the squares of the lengths of said legs.

5. A mathematical model comprising a base, cranks axially mounted therein in fixed angular relation, a flexible filament extending through the extremities of said cranks and forming the outlines of two squares and the legs of a right triangle, and means for simultaneously rotating said cranks to vary the length of the legs of said triangle and to effect an equal variation in the length of the sides of said squares.

6. In a mathematical model, the combination with flexible means forming the legs of a right angle triangle, of means for revolving the vertex of the right angle about the center of the hypotenuse as an axis.

7. In a mathematical model, the combination with flexible means forming the legs of a right triangle, of means remote from the center of the hypotenuse for revolving the vertex of the right angle about said center.

8. In a mathematical model, the combination with flexible means pictorially defining a variable magnitude and a power thereof, of means cooperating with the first means to simultaneously vary the magnitude and the pictorial definition of its power.

9. In a mathematical model, the combination with flexible means pictorially defining a plurality of related magnitudes of the first and second power, of means cooperating with the first means for simultaneously varying the pictorial definitions of the second powers corresponding to variations in the first powers.

10. A mathematical model comprising a base, cranks axially mounted therein, a flexible filament slidably associated with said cranks and pictorially defining a magnitude and a power thereof, and means for simultaneously rotating said cranks to define various magnitudes and their corresponding powers.

11. A mathematical model comprising a base, means associated with said base and adapted to outline the variable legs of a right triangle having a fixed hypotenuse and the variable squares erected upon said legs, and mechanism coacting with said means at points in the loci of the corners of said squares for varying said legs and said squares.

12. A mathematical model comprising a base, means associated with said base and adapted to outline the possible legs of a right triangle having a fixed hypotenuse and the possible squares erected upon said legs, and mechanism comprising a plurality of rotatable arms coacting with said means and axially mounted in the centers of the loci of the corners of said squares for varying said legs and said squares.
